SHUTTLE MECHANISM

John P. Putnam, Boston, Mass., assignor to The
Reece Button Hole Machine Company, Boston,
Mass., a corporation of Maine

Application July 26, 1938, Serial No. 221,311

18 Claims. (Cl. 112—232)

This invention relates to the thread-handling devices of lock-stitch sewing machines, and more particularly to a novel shuttle mechanism thereof.

5 It is the primary aim and object of the present invention to provide a shuttle mechanism wherein the shuttle encounters only negligible frictional resistance even when the same is driven at a very high speed.

10 It is another object of the present invention to construct the shuttle mechanism in such manner that the shuttle may be continuously driven at a uniform speed and at a most favorable 1 to 1 ratio with respect to the needle reciprocation, i. e., one revolution of the shuttle for each

15 needle reciprocation.

It is another object of the present invention to construct the shuttle mechanism in such manner that a thread loop need not be twisted in order to pass around the rotating shuttle without interference from the shuttle drive.

20 The foregoing and other objects of the present invention, together with means whereby the latter may be carried into effect will best be understood from the following description of an illustrative embodiment thereof shown in the accompanying drawing. The particular mechanism described and shown is, however, being chosen for purposes of exemplification merely, 25 as it will be obvious to those skilled in the art that the invention, as defined by the claims hereunto appended, may be otherwise embodied without departure from the spirit and scope thereof.

30 In said drawing:

35 Fig. 1 is a front elevation of a shuttle mechanism which embodies the present invention.

Fig. 2 is a side elevation, partly broken away, of the shuttle mechanism.

40 Fig. 3 is a section taken substantially on the line 3—3 of Fig. 1.

Fig. 4 is a fragmentary section, taken substantially on the line 4—4 of Fig. 1, showing the elements separated, however.

45 Fig. 5 is a perspective view of certain operating elements of the shuttle mechanism shown separated.

Fig. 6 is a view similar to Fig. 5, showing the elements in a modified form, however.

50 The present shuttle mechanism has for a primary feature a novel shuttle drive, certain rotary elements of which not only transmit their rotary motion to the shuttle, but permanently support the latter as well, thereby eliminating the customary shuttle race. Briefly, this is accomplished by providing a cylindrical shuttle, having

5 gear teeth in its periphery which are in permanent mesh with at least two pinions. The teeth of the shuttle interlock with the teeth of the pinions in such manner, and the pinions are so angularly spaced, that the shuttle is held by said pinions against movement in any direction except rotation around its own axis, and is rotated about its axis upon rotation of said pinions.

10 Referring to the drawing, and more particularly to Figs. 1 and 2 thereof, the reference numeral 10 designates a support for the work W to be sewed. This support 10 has the usual opening 11 for the needle 12, and is suitably mounted on any conventional lock-stitch sewing machine (not shown). Depending from said support 10 15 is a bracket 13 in which stub shafts 14 and 14a are journaled. Suitably mounted on the ends of said stub shafts 14 and 14a which project beyond one side of the bracket 13 are identical pinions 15 and 15a, respectively, which are in permanent mesh with the peripheral gear teeth 16 of a cylindrical shuttle 17. The shuttle 17 has a central recess 18 for the reception of the customary bobbin (not shown) which is journaled on a projecting shank 19 of the shuttle 20 and retained thereon by any conventional bobbin retaining means (not shown). Mounted on the ends of the stub shafts 14 and 14a which project beyond the opposite side of the bracket 13 are identical pinions 20 and 20a, respectively, 25 which are in permanent mesh with a common driving gear 21, mounted on a shaft 22 which is journaled in any suitable manner (not shown) in the sewing machine and suitably driven in a certain timed relation with the reciprocations of the 30 needle 12. More particularly the pinion 20a is suitably mounted for rotation together with its stub shaft 14a, while the pinion 20 is freely rotatable on its stub shaft 14 and provided with a projecting lug 23 against which bears a set screw 35 40 24, threadedly received by a radially projecting arm 25 of said stub shaft 14. The shaft 22 is driven in such direction (see arrow 26 in Fig. 2) that the pinion 20 transmits its rotary motion to its stub shaft 14 through intermediation of the lug 23, set screw 24, and arm 25. Rotation 45 of the shaft 22 in the specified direction results in simultaneous counterclockwise rotation of the pinions 15 and 15a and in simultaneous clockwise rotation of the shuttle 17, as viewed in Fig. 1. The pinions 15 and 15a are shown disposed almost diametrically opposite each other, and it can be understood that removal of the shuttle 50 55 55 from engagement with the pinions 15 and 15a in any direction at right angles to its axis is

resisted by the mating teeth of the shuttle 17 and of said pinions. Inasmuch as the pinions 15 and 15a are identical with each other, and inasmuch as the pinions 20 and 20a are also 5 identical with each other but not necessarily identical with the pinions 15 and 15a, it can also be understood that rotation of the shaft 22 results in simultaneous rotation of the pinions 15 and 15a through equi-angular distances so that 10 the shuttle is merely rotated about its own axis but is in no wise bodily moved in any direction at right angles to its axis. It, therefore, follows that the pinions 15 and 15a support the shuttle 17, regardless of whether the latter rotates or 15 is at rest. More particularly, the shuttle teeth 16 are formed in two sets 16a and 16b (Figs. 4 and 5) which are embedded in the shuttle periphery 27 and spaced from the adjacent circular edges thereof by peripheral flanges 28 and 20 29, respectively, of the shuttle. The sets 16a and 16b of shuttle teeth are furthermore separated from each other by an intermediate peripheral flange 30 of the shuttle. The pinions 15 and 15a 25 are of substantially the same width as that of the shuttle periphery, and each pinion is provided with two sets of teeth 15b and 15c (Figs. 4 and 5) which project from the pinion periphery and are spaced apart the same distance as the sets 16a and 16b of shuttle teeth. Thus, each 30 pinion is provided with peripheral portions 31 which extend between the edges of the shuttle periphery and the adjacent sets of teeth 15b and 15c, and with a peripheral portion 32 which extends between said sets of teeth. The peripheral flanges 28, 29 and 30 of the shuttle are adapted to ride on the peripheral portions 31 and 32 of the pinions 15 and 15a, while the sets of teeth 16a and 16b of shuttle teeth are adapted to mesh with the sets of teeth 15b and 15c, respectively, of said pinions. The explained co-operation of the pinions 15 and 15a with the shuttle prevents the axial removal of the latter from engagement with said pinions, guides the shuttle for rotation about its own axis as a fixed 45 axis, and counteracts tendencies of certain forces acting on the shuttle periphery to cock the shuttle with respect to said pinions. These forces, which are directed axially of the shuttle and tend to cock the same are component forces of the resulting pull on the thread of a loop by the rotating shuttle when said loop is passing there-around. The forces for supporting the shuttle 50 17 are transmitted through the engaging peripheral portions of the shuttle 17 and of the pinions 15 and 15a, while the mating teeth of the shuttle and of said pinions retain the shuttle in supporting engagement with the pinions.

The peripheral flanges 28, 29 and 30 of the shuttle 17 are brought into engagement with the 55 peripheral portions 31 and 32 of the pinions 15a and 15, respectively, by manipulating the set screw 24. Thus, on advancing said screw 24 in the lug 25, either the pinion 20 will be rotated clockwise as viewed in Fig. 1, or the stub shaft 60 14 and pinion 15 will be rotated counter-clockwise as viewed in Fig. 1, or both the pinion 20 and the stub shaft 14 will be rotated clockwise and counter-clockwise, respectively, as viewed in Fig. 1, as the case may be. If the pinion 20 65 is rotated clockwise as viewed in Fig. 1, the pinion 15a is also rotated clockwise, as viewed in Fig. 1, through intermediumation of the common driving gear 21, pinion 20a and stub shaft 14a, with the result that the teeth of the pinion 15a draw the 70 shuttle 17 bodily to the right and downwardly 75

as viewed in Fig. 1 until its peripheral flanges 28, 29 and 30 contact the peripheral portions 31 and 32 of the pinions 15a and 15, respectively. If the stub shaft 14 and the pinion 15 are rotated counter-clockwise as viewed in Fig. 1, the same 5 result is obtained except that it is then the pinion 15 which draws the shuttle to the right and downwardly as viewed in Fig. 1 until its peripheral flanges 28, 29 and 30 contact the peripheral portions 31 and 32 of the pinions 15a 10 and 15, respectively. When both pinions 20 and 15 are rotated clockwise and counter-clockwise, respectively, as viewed in Fig. 1, each of these pinions performs in the above mentioned manner with the result that the shuttle is drawn to the right and downwardly as viewed in Fig. 1 until its peripheral flanges 28, 29 and 30 contact the peripheral portions 31 and 32 of the pinions 15a and 15, respectively. Hence, the peripheral flanges 28, 29 and 30 of the shuttle 17 are forced 20 into firm engagement with the peripheral pinion portions 31 and 32 by merely manipulating the set screw 24.

The shuttle 17 is also provided with a groove 36 which extends across the periphery of the 25 shuttle in the skewed fashion shown in Figs. 3 and 5. A side wall 36a of said groove 36 and a portion of the front face 37 of the shuttle merge into a hook 38 which projects slightly beyond said front face 37 as best shown in Fig. 3. The 30 sets 16a and 16b of shuttle teeth are interrupted adjacent the groove 36 in the manner best shown in Fig. 5, requiring a corresponding interruption of the sets of teeth 15b and 15c of the pinions 15 and 15a as can be readily understood. Thus, the sets of teeth 15b and 15c of the pinions 15 and 15a are in reality gear segments and the sets 35 16a and 16b of shuttle teeth are likewise gear segments. Permanent driving engagement between the pinions 15 and 15a and the shuttle 40 is maintained because the gear segments 16a, 16b of said shuttle as well as the gear segments 15b, 15c of said pinions overlap in the fashion shown in Fig. 5, with the result that the aligned end teeth 40 of the pinion segments 15b and 15c 45 mate with the aligned tooth cavities 39 of the shuttle segments 16a and 16b and thus establish a driving link across the intervening gaps between the end teeth of said gear segments. The pinions 15 and 15a may be disposed in an angularly spaced relation other than that illustrated in Fig. 1. However, several requirements, to be explained hereafter, fix a definite angular range within which said pinions may be disposed. Thus, the pinions 15 and 15a must be so angularly spaced from each other that their teeth 50 prevent the lateral removal of the shuttle from engagement with said pinions. It is also imperative that the pinion 15 meshes with the shuttle teeth at a station where a thread loop 1, just caught by the hook 38 in the manner illustrated in Figs. 1 and 2, has already been deflected into the skewed groove 36 by the edge 36a thereof (Fig. 5). In so disposing the pinion 15, the same can never interfere with the passing 55 loop 1 because the latter is then drawn against the bottom of the shuttle groove 36 which is in closer proximity to the shuttle axis than the shuttle periphery 27. It is also imperative that the gaps between the end teeth of the gear segments 15b, 15c of the pinions 15 and 15a bridge the groove 36 every time the latter passes said pinions. This is accomplished by properly initially correlating the pinions 15 and 15a with the shuttle teeth 16, and by making the ratio 60 70 75 80 85 90 95 100 105 110 115 120 125 130 135 140 145 150 155 between the number of shuttle teeth and the number of teeth of each of said pinions a whole number. If the number of teeth of each pinion did not divide evenly into the number of teeth 5 of the shuttle, the intervening gap between the teeth of the pinions 15 and 15a would obviously not bridge the shuttle groove 36 every time the latter passes said pinions. By complying with the latter requirements, a non-twisted thread 10 loop may be passed around the rotating shuttle without interference from the pinions 15 and 15a. Also, in order to obtain a most favorable 1 to 1 ratio between the shuttle speed and the needle reciprocations, i. e., one revolution of the shuttle 15 to each needle reciprocation, a thread loop 1 must be passed around the shuttle during a minimum part of one revolution thereof, so that the take-up device may perform its well-known operation and the needle 12 may go through the well 20 known motions to cast a new loop 1 into the path of the shuttle hook while the shuttle rotates through the remaining part of the same revolution. To accomplish this, the pinion 15a has to be spaced a considerable angular distance from 25 the needle 12 (see Fig. 1), as can be readily understood. In order to take up any play or backlash between the mating teeth of the shuttle 17, the pinions 15, 15a and 20, 20a and the driving gear 21, the set screw 24 is manipulated against 30 the lug 23 of the pinion 20.

Fig. 6 shows cooperating elements of a modified shuttle drive in which the gear segments 16a and 16b of the shuttle 17a merge into the side walls of the groove 36 and the teeth of the 35 pinions (only one being indicated at 15d) are interrupted at 46 only in order to avoid a thread loop 1, lying against a slanting bottom of the groove 36 which has its shallow part in alignment with the gap 46 of each of said pinions.

It is also within the scope of the present invention to provide shuttle-supporting pinions, the teeth of which may be continuous around the periphery and not at all interrupted by a skewed 40 gap such as that of the pinion 15 shown in Fig.

5. In that case, the entire bottom of the groove 45 36 in the shuttle periphery must be disposed in closer proximity to the shuttle axis than the pinion teeth which are in mating engagement with the shuttle teeth, in order to avoid any interference of said pinion teeth with a non-twisted thread loop passing around the rotating 50 shuttle.

I claim:

1. A shuttle mechanism comprising, in combination, a shuttle, and two elements cooperating to support the shuttle at all times and to rotate the same about its own axis through any angular distance and in either direction, each element being a driving element.

2. A shuttle mechanism comprising, in combination, a shuttle, and two elements cooperating to support the shuttle at all times and to rotate the same about its own axis through any angular distance, each element being a driving element and so coordinated with the shuttle as to permit the thread of a non-twisted loop to pass unobstructedly, around said shuttle.

3. A shuttle mechanism comprising, in combination, a shuttle, and revolving driving elements 70 for said shuttle, said elements also permanently supporting the shuttle.

4. A shuttle mechanism comprising, in combination, a shuttle having a cylindrical periphery provided with gear teeth; and at least two pinions 75 in permanent mesh with the shuttle teeth and

adapted to support the shuttle at all times and to rotate the same about its own axis.

5. A shuttle mechanism comprising, in combination, a shuttle having a cylindrical periphery provided with gear teeth; and two pinions in 5 permanent mesh with the shuttle teeth and adapted to support the shuttle and to rotate the same about its own axis, said pinions being interlocked with the shuttle teeth so as to resist removal of the shuttle from said pinions in any 10 direction.

6. In a shuttle mechanism, the combination of a shuttle having a cylindrical periphery provided with gear teeth; and at least two pinions in permanent mesh with the shuttle teeth and adapted 15 to support and rotate said shuttle, the shuttle and said pinions having interfitting peripheral deformations which together with the meshing teeth of the shuttle and pinions prevent any movement of the shuttle relative to said pinions 20 other than rotation about its own axis as a fixed axis.

7. In a shuttle mechanism, the combination of a shuttle having a cylindrical periphery provided with gear teeth and a skewed groove traversing said toothed periphery, said groove having its bottom closer to the shuttle axis than the root circle of said gear teeth and being adapted to receive the thread of a non-twisted loop; and at least two pinions in permanent mesh with the 30 shuttle teeth and adapted to support and drive the shuttle.

8. In a shuttle mechanism, the combination of a shuttle having a cylindrical periphery provided with gear teeth; and at least two pinions in permanent mesh with the shuttle teeth and adapted to support and rotate the shuttle, said shuttle and said pinions having laterally spaced, interfitting peripheral deformations through which the shuttle supporting forces are transmitted and 40 which together with the meshing teeth of the shuttle and pinions prevent any movement of the shuttle relative to said pinions other than rotation about its own axis.

9. In a shuttle mechanism, the combination of a shuttle having a cylindrical periphery provided with gear teeth and a skewed groove traversing said toothed periphery and having its bottom tapered, said groove being adapted to receive the thread of a non-twisted loop; and a pinion in 50 permanent mesh with the shuttle teeth, the toothed periphery of said pinion being traversed by a skewed groove which coincides with the shuttle groove once during each revolution of the shuttle and terminates at a point adjacent to 55 where the bottom of the shuttle groove commences to be closer to the shuttle axis than the root circle of the shuttle teeth.

10. In a shuttle mechanism, the combination of a cylindrical shuttle having peripheral gear 60 teeth separated by an intermediate peripheral deformation and flanked on both sides by two other peripheral deformations; and at least two pinions in permanent mesh with the shuttle teeth and adapted to support and rotate said 65 shuttle, said pinions having peripheral deformations interfitting with those of the shuttle to prevent in conjunction with the meshing teeth of the shuttle and pinions any movement of said shuttle relative to said pinions other than 70 rotation about its own axis as a fixed axis.

11. In a shuttle mechanism, the combination of a rotary shuttle having a cylindrical periphery provided with gear teeth, a groove in said periphery and a hook at one end of and merging 75 into said groove; and a pinion in mesh with the

- shuttle teeth, said groove being so skewed and said shuttle teeth being so interrupted at said groove that the pinion will remain in permanent mesh with the shuttle teeth when passing said groove.
- 5 12. In a shuttle mechanism, the combination of a rotary shuttle having a cylindrical periphery provided with axially spaced sets of gear teeth, a skewed groove so traversing the gear teeth that either set is uninterrupted by said groove within a peripheral region axially aligned with the gap in the other set as caused by said groove, and a hook at one end of and merging into said groove; and a pinion in mesh 10 with the shuttle teeth.
- 15 13. In a shuttle mechanism, the combination of a rotary shuttle having a cylindrical periphery provided with gear teeth, a groove in said periphery and a hook at one end of and merging 20 into said groove; and a pinion in mesh with the shuttle teeth and having a peripheral groove traversing its own teeth and coinciding with the shuttle groove when said pinion passes the latter, said grooves being so skewed and said teeth 25 being so interrupted at said grooves that the pinion will remain in permanent mesh with the shuttle teeth when passing the shuttle groove.
14. A shuttle mechanism comprising, in combination a shuttle having a cylindrical periphery 30 provided with gear teeth; a plurality of pinions in mesh with the shuttle teeth, a non-toothed annular portion of the shuttle periphery riding on non-toothed annular portions of the pinion peripheries which form the sole support 35 for said shuttle; and a device for driving said pinions simultaneously in the same direction and at the same peripheral speed, said device including means for taking up any back-lash between the shuttle teeth and the pinion teeth.
- 40 15. A shuttle mechanism comprising, in com-

bination, a shuttle having a cylindrical periphery provided with gear teeth; two pinion elements in mesh with the shuttle teeth, a non-toothed annular portion of the shuttle periphery riding on non-toothed annular portions of the pinion peripheries which form the sole support for said shuttle, and said pinion elements being so angularly spaced that the meshing pinion and shuttle teeth lock the shuttle against lifting from said annular pinion portions; and a device for 10 driving said pinion elements simultaneously in the same direction and at the same peripheral speed, said device including means for taking up any back-lash between the shuttle teeth and the pinion teeth.

15 16. The combination in a shuttle mechanism as set forth in claim 15, in which said device includes two gear elements, one of which is rotatable with one of the pinion elements, a driving connection between the other gear element and 20 the other pinion element, said connection being adjustable to cause such relative rotation between said other elements that the shuttle is drawn into firm supporting engagement with the pinion elements, and a common driving gear in 25 mesh with said gear elements.

17. The combination in a shuttle mechanism as set forth in claim 15, in which said device includes two gear elements, one of which is rotatable with one of the pinion elements and 30 the other of which is rotatable relative to the other pinion element coaxially thereof, eccentrically located lugs on said other elements, a set screw threadedly received in one of said lugs and contacting the other lug, and a common driving gear in mesh with said gear elements.

35 18. The combination in a shuttle mechanism as set forth in claim 15 in which said means is a single manually operable element.

JOHN P. PUTNAM. 40
